CLAIM

The ornamental design for a loudspeaker housing, as shown and described.

DESCRIPTION

FIG. 1 is a perspective view of a loudspeaker housing showing our new design;

FIG. 2 is a front elevational view thereof;

FIG. 3 is a rear elevational view thereof;

FIG. 4 is a side elevational view, the opposite side elevational view being a mirror image thereof;

FIG. 5 is a top plan view thereof; and,

FIG. 6 is a bottom plan view thereof.

The broken line showings of the rectangle on the front face, the handle grips, the rectangle on the rear face, and the rectangle on the top surface are for illustrative purposes only and form no part of the claimed design.
